UNITED STATES PATENT OFFICE.

DANIEL MERCIER, OF ANNONAY, ARDÈCHE, FRANCE.

DRUM FOR MACHINES FOR STRETCHING HIDES AND SKINS.

1,126,057.

Specification of Letters Patent.

Patented Jan. 26, 1915.

Original application filed September 11, 1913, Serial No. 789,222. Divided and this application filed May 5, 1914. Serial No. 836,417.

To all whom it may concern:

Be it known that I, DANIEL MERCIER, citizen of the Republic of France, residing at 3 Rue Basse Ste. Claire, Annonay, Ardèche, in the Republic of France, have invented new and useful Improvements in Drums for Machines for Stretching Hides and Skins, of which the following is a specification.

10 This invention relates to a drum for stretching and softening machines used in treating tanned and chrome-tanned hides and skins, the said drum being more particularly adapted for use in treating the edges 15 of the hide.

The present application is a division of my co-pending application for patent, Serial Number 789,222, filed September 11th, 1913.

20 In the annexed drawing given by way of example: Figure 1 is a view, partly in section, of the improved drum for treating the edges of the hide. Figs. 2, 3 and 4 are enlarged details of the blades mounted on said 25 drum, Figs. 3 and 4 being cross sections along the lines A—A and B—B, respectively, of Fig. 2.

The stretching drum 1^a for the edges of the hide is of a generally cylindrical shape 30 and keyed concentrically on its shaft 2^a which is rotated by any suitable means. The blades 11 secured on its periphery are arranged radially. Their edge has a slight convexity from one end to the other and is provided with rounded notches 12 spaced 35 by solid parts 13. The edges of the blades have a rectangular cross section in the parts 13 as shown in Fig. 3, and a rounded cross section in the notches 12 (Fig. 4). The 40 rounded parts of the blade edges merge progressively into the rectangular parts so as to form no abrupt points or corners by

which the hide treated might be damaged. The blades are preferably so arranged that the notches 12 in one blade are in alinement 45 with the solid parts 13 of the next succeeding blade. The hide to be dressed is held on the periphery of the drum by means of a brush, a leather band, or the like. The drum so constructed permits of finishing 50 the dressing of the hide in a very efficient manner, by drawing and softening the edges in all directions while exerting a slight scraping effect.

Having now described my invention, 55 what I claim as new and desire to secure by Letters Patent is:

1. In a machine for stretching hides and skins, the combination of a shaft, a stretching drum carried on said shaft, blades secured radially on the periphery of said 60 drum, said blades being provided with notches the edge of each blade being rounded in the notches and square in the spaces between the notches, substantially as de- 65 scribed and for the purpose set forth.

2. In a machine for stretching hides and skins the combination of a shaft, a stretching drum, carried on said shaft; blades secured radially on the periphery of said 70 drum, said blades having a curved edge from end to end and being provided with notches, the edge of each blade being rounded in the notches and square in the spaces between the notches, substantially as 75 described and for the purpose set forth.

In testimony whereof I have signed my name to this specification in the presence of two subscribing witnesses.

DANIEL MERCIER.
